UNITED STATES PATENT OFFICE.

JOSEPH M. DUBY, OF MEDFORD, AND JOSEPH L. EDMESTER, OF CHELSEA, MASSACHUSETTS.

ELECTRIC BELL-COUPLER FOR STEAM-RAILROADS.

SPECIFICATION forming part of Letters Patent No. 366,654, dated July 19, 1887.

Application filed January 8, 1887. Serial No. 223,826. (No model.)

To all whom it may concern:

Be it known that we, JOSEPH M. DUBY and JOSEPH L. EDMESTER, citizens of the United States, residing, respectively, at Medford, in the county of Middlesex and State of Massachusetts, and at Chelsea, in the county of Suffolk and State of Massachusetts, have invented a certain new and useful Improvement in Connectors or Couplers for Electrical Conductors, 5 of which the following is a specification, reference being had to the accompanying drawings, wherein—

Figure 1 is a perspective view of our improved coupler. Fig. 2 is a longitudinal vertical section thereof. Fig. 3 is a similar section, the members of the coupler being shown as separated. Fig. 4 is also a similar section, showing one member connected with a dummy.

The same numerals of reference have been 20 applied to corresponding parts in the several views.

Our invention has for its object to provide an improved coupler for two electric wires forming a safety-signal circuit for trains, the 25 members of which coupler may be detached or uncoupled from each other by hand without breaking circuit; but which, if forcibly or accidentally uncoupled, as by the breaking of the train and the separating of the cars, will 30 break the electrical circuit and sound an alarm-bell in the cab of the engine. We accomplish this object by means of the mechanism illustrated in the accompanying drawings, in which the coupler is represented as composed of two 35 similar members, marked 1 and 2, respectively.

The body of each member is constructed of non-conducting material, and is preferably cylindrical in cross-section. Each member is provided with a tongue, *a*, projecting from its 40 face, and a recess, *b*, adjacent thereto adapted to receive the tongue *a* of the fellow member, as most clearly shown in Fig. 3. The tongue is preferably semicircular in cross-section and the recess of corresponding shape. Each 45 member is provided with a cap, 3, screwed upon its outer end. Each cap has a central opening, through which the two wires 9 and 10 of the cable *c* enter the coupler at its opposite ends, said wires diverging within the 50 cap to diametrically-opposite points. One of these wires, 9, is connected with a copper plate,

11, which is secured at one end to the tongue *a* and extends along the flat face thereof and along the interior of the member to near the outer end thereof. The other wire, 10, is carried through the body of the member to the inner end thereof, where it is in electrical connection with a metallic conducting-ring, 4, secured to the end of the member. 55

A bushing, 7, is screwed radially into the body of each member of the coupler on the opposite side of the recess from the plate 11, and through this bushing extends a push-pin, 8. A bent spring, 12, is connected at one end to the outer end of the plate 11, and its other 55 end extends into the recess, *b*, and is adapted to automatically make connection with the bushing 7. The wire 10 in its passage through the coupler is given a turn around said bushing. 70

In the cab of the locomotive, or at any other convenient point, is placed a battery, and in circuit an alarm-bell operated by spring mechanism, in the usual manner. When the circuit is broken, even for an instant, said spring 75 mechanism is set in motion and an alarm sounded.

In the use of our improved coupler it is designed that one member thereof be attached to the cable at the rear of the tender and one 80 member to the cable at each end of each car, and the two members at the meeting ends of adjacent cars are united to form the coupling. In this normal position of the members the current passing over the wires from one pole 85 of the battery then flows through the two plates 11 and springs 12, which are in contact and by which the members of the coupler are held together, and from the other pole through the wires 10 and end plates, 4, which are also 90 in contact.

In the operation of uncoupling the members the push-pin 8 is pressed upon until its inner end comes in contact with the spring 12, thus short-circuiting the car, and as soon as 95 the tongue *a* is withdrawn from the recess *b* the pressure on the push-pin may be released, and the spring 12 will follow it and continue in electrical connection therewith, whereby the circuit will remain closed; but if the 100 members of the coupler are forcibly detached the circuit is interrupted for an instant and

the alarm mechanism tripped and set in motion. In the operation of coupling the members the push-pins are also pressed upon before the members are interlocked, whereby the circuit is preserved and the coupling effected without sounding an alarm. When one member constitutes the end of the line at the end of a train, the spring 12 automatically forms contact with the bushing 7 and completes the circuit.

In Fig. 4 is illustrated a "dummy" member, 14, attached by a bar, 15, to the end of the car, in which the coupler may be placed when it is desired to hold the circuit open.

Separable metallic connectors 13 may be employed, if desired, for connecting the line-wire within the car with the cables *c*, which extend between the cars. Each of these connectors comprises a metallic plate, 16, which is secured to the end of the car, and a metallic plate, 17, which is detachably keyed to the latter by a dovetail spline or key, 18, of one plate fitting into a dovetail groove of the other plate. The line-wire which extends through the car has its outer end connected to the plate 16 by being passed through the hole 19 and secured to the binding post or screw 20. The end of the cable *c*, or of one of its branches, is connected to the metallic plate 17 at 21. When the electric signaling apparatus is in use, the two plates 16 and 17 are united; and in case the apparatus be not used the flexible cables extending beyond the ends of the cars for connecting the line of one with that of another may be taken off by detaching the plate 17 from the plate 16.

Having thus described our invention, we claim—

1. An electrical coupler for the two wires of an alarm on railroad-trains, each member of which comprises a body provided with a tongue and recess adapted to engage the tongue and recess on the fellow member, a metallic

plate on the flat face of said tongue, a metallic ring on the end of said member, and electrical connections between said plate and ring and the line-wires, respectively, substantially as described.

2. An electrical coupler for the two wires of an alarm on railroad-trains, each member of which comprises a body provided with a tongue and recess adapted to engage the tongue and recess on the fellow member, a metallic plate on the flat face of said tongue, a metallic ring on the end of said member, electrical connections between said plate and ring and the line-wires, respectively, and a spring secured to the face of said plate, substantially as described.

3. An electrical coupler for the two wires of an alarm on railroad-trains, each member of which comprises a body provided with a tongue and recess adapted to engage the tongue and recess on the fellow member, a metallic plate on the flat face of said tongue, a metallic ring on the end of said member, electrical connections between said plate and ring and the line-wires, respectively, a bushing in the body of the coupler in circuit with the ring, a push-pin within said bushing, for the purpose set forth, and a spring secured to the face of said plate at its outer end, its inner end being adapted to impinge upon and form electrical contact with the bushing or push-pin of the fellow member, substantially as described.

4. A connector for electric conductors comprising two metallic plates provided, respectively, with means for attaching the ends of the conductor, one of said plates being provided with a dovetail key and the other with a dovetail groove, substantially as described.

JOSEPH M. DUBY.

JOSEPH L. EDMESTER.
